FRANK E. FOWLER, OF ATHENS, GEORGIA

MECHANICAL STOP FOR BOTTLE CAPPING MACHINES

Application filed May 19, 1930. Serial No. 453,800.

This invention relates to improvements in bottle capping machines and has for an object the provision of means for automatically stopping the operation of the machine in the event of failure to cap a bottle, the present application being a companion case to application Serial No. 284,619, filed June 11, 1928.

The application referred to discloses means for automatically interrupting an electric circuit to stop the operation of the capping machine in the event of failure to cap a bottle, while the present application provides means for throwing out the clutch which controls the operation of the machine, so that the machine is stopped without stopping the motor when the machine fails from any cause to cap a bottle.

With the above and other objects in view, the invention further includes the following novel features and details of construction, to be hereinafter more fully described, illustrated in the accompanying drawings and pointed out in the appended claims.

In the drawings:—

Figure 1 is a perspective view showing a fragmentary portion of a bottle capping machine with the invention applied.

Figure 2 is an elevation partly in section of the invention per se.

Figure 3 is a bottom plan view of the subject matter of Figure 2.

Figure 4 is a section on the line 4—4 of Figure 2.

Figure 5 is a plan view of the clutch lever carried member.

Referring to the drawings in detail wherein like characters of reference denote corresponding parts, the invention is shown as applied to a portion of a bottle capping machine wherein the magazine head is vertically movable and also oscillates horizontally. This head is indicated at 10 and receives the necks of the bottles which are moved into position by means of a feed device indicated at 11 and guided by means of a guide 12. The bottles B are in position for capping, while the bottles b have passed this position and have already been capped, while the bottle b' remains uncapped.

The machine as thus far described is of a type in common use and forms no part of the invention, except that the magazine head is utilized for the support of the invention, while the movement of the head is utilized in its operation. With this in view, there is attached to the magazine head as shown at 13, a bracket 14. This bracket carries spaced capping units, each of which includes cylindrical members 15, the spacing of the units being equal to the spacing of the bottles as the latter pass through the machine. The cylindrical members 15 are closed at their inner ends and are attached to the bracket 14 by any suitable means indicated at 16.

Movable within the cylindrical member 15 is a plunger 17, which is yieldingly held against inward movement by a spring 18. One end of this spring is seated within a socket 19 provided in the plunger, while its opposite end bears against the screw 16, or against the inner end of the cylinder.

Slidable upon the cylinder 15 is a sleeve 20 and this sleeve carries an outwardly extending arm 21, the arms of the sleeves of the adjacent units extending inward or toward one another. Movement of the sleeve upon the cylinder 15 is limited by means of a stop screw 22 which is carried by the cylinder and which extends through a slot 23 provided in the sleeve. The sleeve is yieldingly held in raised position and in engagement with the bracket 14, by means of a spring 24. One end of this spring is attached to the sleeve and the opposite end is attached to the cylinder.

Surrounding the plunger 17 is a flange or collar 25. This flange or collar is notched as at 26 and pivotally mounted within this notch upon a pivot pin 27 is a latching dog 28. This dog has its bill normally forced outward by means of a spring pressed plunger 29, and this bill is adapted to engage a shoulder 30, which surrounds the inner end of the sleeve 20. When the shoulder is engaged by the dog 28, the sleeve will be held in its lowermost position.

Mounted for limited sliding movement upon the lower end of the plunger 17 is a bottle neck engaging head 31. This head is

provided with a seat 32 for engagement by the mouth of the bottle while extending from this seat is an outwardly flared inclined flange 33 which guides the mouth of the bottle within the seat. The head 31 is socketed as shown at 34 to receive the lower end of the plunger 17, while a headed screw or stud 35 which is carried by this plunger extends through and beyond the seat 32. Movement of the head 31 in an upward direction is limited by the collar 25, while movement in an opposite direction is limited by the head of the screw 35. Upward movement of the capping head is yieldingly resisted by a spring 36 which surrounds the screw 35.

Guided in the bracket 14 and arranged in the path of upward movement of either of the arms 21 of the capping units is a rod 37. Upward movement of the rod is limited by a head 38 which engages the lower end of a guide nipple 39. The rod 37 is normally positioned as shown by the dotted lines in Figure 2 so that the upper end of this rod is disposed only slightly above the upper face of the bracket 14.

Extending from the usual clutch lever 40 which operates a clutch (not shown) to control the operation of the machine, is an arm 41. The outer end of this arm carries a hook 42, while its inner end is rigid with a sleeve 43. This sleeve is swiveled upon a spool 44 which is adjustably mounted upon the lever 40 by means of set screws 45. The sleeve 43 is thus swiveled upon the lever 40 and is rotatable upon said lever, rotary movement being limited by a pin 46 which is carried by the sleeve and which engages spaced shoulders 47 provided in the spool 44. A torsion spring 48 acts to yieldingly hold the pin against one of the shoulders as shown in Figure 5 of the drawings. Normally, the bottle neck engaging units are arranged as shown at the right of Figure 2 of the drawings, with the sleeves 20 in their lowermost positions and held in such positions by the dogs 28. The rod 37 will then rest upon the arms 21 and will be in the position shown by the dotted lines in Figure 2. With the parts in this position, vertical and oscillatory movement of the head will occur during the operation of the capping machine without the rod engaging the hook 42. Should one of the bottles, for example the bottle b', fail to receive a cap, the mouth 55 of the bottle will engage the seat 32 and when the vertically movable head descends, the head 31 will be forced upward. This head is provided with an inclined top 49 which engages the lower inclined end of the latching dog 28 and moves this end of the dog pivotally outward to release the sleeve 20. This sleeve, under the action of the spring 24 will move upward and will carry the rod 37 upward so that when the head moves horizontally to the left, the rod will engage

the hook 42 and move the lever 40 to disengage the clutch. This position of the parts is illustrated at the left in Figure 2 of the drawings. The arm 41 being mounted on the lever 40 for a limited yieldable movement is to permit said arm 41 to swing a distance sufficient for the passing of the rod 37 so that the latter may engage the hook during the oscillating movement of the magazine head when a bottle fails to receive a cap.

The capped bottles will enter the head and when the vertically movable machine head descends, the head of the screw 35 will engage the cap of the bottle and will force the cap into position upon the bottle. This operation will be repeated until one of the bottles fails to receive its cap.

While the invention is shown as applied to a specific type of machine, it is not the purpose of the present application to restrict the invention in this particular, as it may, with minor changes, be applied to other types of bottle capping machines.

The invention is susceptible of various changes in its form, proportions and minor details of construction and the right is here reserved to make such changes as properly fall within the scope of the appended claims.

Having described the invention what is claimed is:

1. In a bottle capping machine, a vertically movable oscillatory head and means to feed bottles past the head for capping, means including a lever to control the operation of the machine, and means operable when an uncapped bottle passes the head to actuate the lever and stop the operation of the machine automatically.

2. In a bottle capping machine, a vertically movable oscillatory head and means to feed bottles past the head for capping, means including a lever to control the operation of the machine, spaced bottle neck engaging units arranged in the path of the bottles after the latter receive caps, and means operated by either of the units and controlled by an uncapped bottle to actuate the lever and stop the machine automatically.

3. In a bottle capping machine, a vertically movable oscillatory head and means to feed bottles past the head for capping, means including a lever to control the operation of the machine, a bottle neck engaging unit arranged in the path of the bottles after the latter receive caps, and means operable by said unit and controlled by an uncapped bottle to actuate the lever and stop the machine automatically.

4. In a bottle capping machine, a vertically movable oscillatory head, means to feed the bottles past the head to receive caps, a bottle neck engaging unit arranged in the path of the bottles after the latter receive caps, means including a lever to control the opera-

tion of the magazine, a lever carried member, and normally inactive means movable into position to engage the lever and stop the machine automatically when the bottle neck 5 engaging unit engages an uncapped bottle.

5. In a bottle capping machine, a vertically movable oscillatory head, means to feed the bottles past the head to receive caps, a bottle neck engaging unit arranged in the 10 path of the bottles after the latter to receive caps, means including a lever to control the operation of the magazine, a lever carried member, a vertically movable rod, and means carried by the bottle neck engaging unit to move the rod into position to engage the lever carried member and stop the machine 15 automatically when the bottle neck engaging unit engages an uncapped bottle.

6. In a bottle capping machine, a vertically 20 movable oscillatory head, means to feed the bottles past the head to receive caps, a bottle neck engaging unit arranged in the path of the bottles after the latter receive caps, said unit including a cylinder, a spring 25 influenced plunger extending from the cylinder, a spring influenced sleeve slidable upon the cylinder, a lever for controlling the machine, a vertically movable rod, an arm carried by the sleeve to engage the rod and move 30 the latter into position to engage the lever to actuate said lever and stop the machine automatically, means to hold the sleeve against inward movement, and means actuated by contact with an uncapped bottle to 35 release the sleeve holding means.

7. In a bottle capping machine, a vertically 40 movable oscillatory head, means to feed the bottles past the head to receive caps, a bottle neck engaging unit arranged in the path of the bottles after the latter receive caps, said 45 unit including a cylinder, a spring influenced plunger extending from the cylinder, a spring influenced sleeve slidable upon the cylinder, a lever for controlling the machine, a vertically 50 movable rod, an arm carried by the sleeve to engage the rod and move the latter into position to engage the lever to actuate said lever and stop the machine automatically, a plunger carried spring influenced latch 55 normally engaging the sleeve to hold the latter against upward movement, and means actuated by contact with an uncapped bottle to actuate the latch and release the sleeve.

In testimony whereof I affix my signature.

FRANK E. FOWLER.
